CLAIM

The ornamental design for a corkscrew, as shown and described.

DESCRIPTION

FIG. 1 is a top perspective view of a corkscrew showing my new design.

FIG. 2 is a top perspective view of the corkscrew in an open position.

FIG. 3 is a top plan view of the corkscrew in the closed position.

FIG. 4 is a bottom plan view of the corkscrew in the closed position.

FIG. 5 is a front elevation view of the corkscrew in the closed position.

FIG. 6 is a rear elevation view of the corkscrew in the closed position.

FIG. 7 is a left side elevation view of the corkscrew; and, FIG. 8 is a right side elevation view of the corkscrew.
